Int. Cl. D6—01

U.S. Cl. D33—2

FIG. 1 is a perspective view of a bookrack or similar article embodying my new design.

FIG. 2 is a view in side elevation of the bookrack shown in FIG. 1.

FIG. 3 is an end view of the bookrack shown in FIGS. 1 and 2 looking at the bookrack from the end thereof shown as being the left-hand end in FIG. 2 and the right-hand end in FIG. 1.

The surfaces not shown are substantially the same as those of the corresponding surfaces shown.

I claim:

The ornamental design for a bookrack or similar article, as shown and described.
